UNITED STATES PATENT OFFICE

2,453,985

FLUID HEATER

Nelson G. Goreau, New Orleans, La.

Application June 19, 1945, Serial No. 600,365

6 Claims. (Cl. 122—250)

1

My invention relates to Fluid heaters in the nature of an improvement on my prior patent, No. 1,346,952, and relates particularly to heaters of the instant flash type. While intended more particularly for heating water, it may be employed for heating other fluids.

One of the objects of the present invention is to obtain an increase in the thermal efficiency of the heater by providing an improved construction which embodies a casing lined with porous insulating refractory material enclosing a combustion chamber, the walls of which are rapidly heated to incandescence by a suitable fuel burner, and placing a helical coil therein in close proximity to said lining and thereby exposing the major part of the helical coil to the intense heat radiated from the surface of the combustion chamber, thereby producing the very highest thermal efficiency while employing the least amount of coil and other material embodied in the heater.

Another object is to provide a preheating coil above and in series with main helical coil which is heated principally by convection in order to conserve heat.

Another object is to so arrange the convolutions of the coils that they will be narrowly spaced apart and that the condensate, which condenses thereon, will be conveyed away from the lower helical coil and combustion chamber and to evaporate it within the heater.

Another object is to make the heater safe by reducing the volumetric contents of the combustion chamber by venting the top and bottom of the structure, thereby relieving any abnormal pressure due to accidental ignition of gas therein.

The novel features, which I believe to be characteristic of my invention, are set forth with particularity in the appended claims. The invention itself, however, both as to organization and method of operation, together with additional objects and advantages thereof, will be best understood from the following description of a specific embodiment when read in connection with the accompanying drawings, in which,

Fig. 1 is a view of the heater partly in vertical section and partly in side elevation.

Fig. 2 is a sectional plan view on the line 2—2 of Fig. 1 and partly broken away.

Referring to the construction shown in the drawings for the purpose of illustrating the principles involved in the invention, the numeral 7 designates an outside vertical annular casing which may be constructed of any suitable material. This casing has a lining 8 of porous insu-

2

lating refractory material which encloses a combustion chamber. This lining is bellmouthed at its lower end and is cylindrical at its upper end but its main portion is diverging upwardly.

5 The combustion chamber contains a helical coil 10 in proximity to the lining 8 so as to be heated by radiation from the highly heated lining. The convolutions of this coil are narrowly spaced apart and converge downwardly so that water condensing thereon will be conveyed away from the lower convolution and from the combustion chamber.

The upper end of the coil 10 is connected with the lower outer end of spiral preheating coils 12, 15 the outer convolutions of which are very close to the cylindrical portion of the lining 8, so that these coils are heated principally by convection. A spider with arms 13, inclined downwardly toward the center, is located below the coils 12.

20 Positioned centrally within the coil 10, there is a cup-like casing 14 which has a bottom 16 and is coned upwardly in spaced relation from the coil. It will be noted further from the drawings that the convolutions of the coil 10 in upward 25 direction gradually approach closer and closer to the lining 8 while they gradually become positioned farther and farther from the casing 14. The lower end of a rod 18 is secured to the bottom of 16 by nuts 20. The rod 18 toward its

30 upper end is secured to the arms 22 of a spider by a nut 24. The upper sides of the arms 22 are provided with vent passages 34. Standards 26 extend up from the arms 22 and support a down draft deflector 28. An escape vent pipe 30 is secured to the upper portion of the standards 26. A cover member 32 is supported at the outer ends of the arms 22 and is centrally apertured for the pipe 30, around which it is free to slide upwardly. A cold water supply pipe 36 is connected with 35 the outer end of the coils 12.

An annular drip pan 102 is positioned below the casing 7 to collect water which may drip from inside of the combustion chamber. The inner casing 14 serves as a receptacle to collect 40 water which condenses on the upper coils 12 and runs down the inclined spider arms 13.

The water which collects in these receptacles is quickly evaporated by heat from a burner 88 supplied by a gas pipe 86. An opening 104 over 45 the pan 102 supplies secondary air to the combustion chamber while an opening 106 through the center of the pan supplies primary air to the burner.

The operation and advantages of this fluid 50 heater will be apparent in connection with the

foregoing description and the accompanying drawing. Referring to the drawings, it is to be noted that the space between the lining 8 and the cup-shaped member 14 constitutes a combustion chamber that is annular and generally of truncated cone in shape; that 10 designates a spiral coil having spaced convolutions which divides said chamber diagonally to form a diminishing inlet combustion chamber and an expanding outlet flue; and that the numeral 88 designates a fuel burner for projecting flame initially into said inlet chamber and then in succession between said spaced convolutions into said outlet flue.

If a large amount of gas in the combustion chamber should become ignited, it will lift the safety cover 32 to relieve pressure in the chamber and prevent damage to the structure. The down-draft deflector 28 in conjunction with the cover 32 provides for adequate venting through the vent passages 34 in the arms 22.

I claim:

1. In combination with a fluid heater having a combustion chamber that is annular and generally of truncated cone in shape and a spiral coil having spaced convolutions, divides the chamber in a diagonal direction to form a diminishing inlet combustion chamber and an expanding outlet flue, and a fuel burner for projecting flame initially into said inlet chamber and then in succession between said spaced convolutions into said outlet flue.

2. The combination stated in claim 1, and a drip pan at the bottom of the heater for receiving and evaporating condensate from said coil.
5. 3. The combination stated in claim 1, and means for admitting primary and secondary air into said burner.
- 10 4. The combination stated in claim 1, and a spiral preheating coil above the exhaust flue connected in series with the aforesaid spiral coil.
5. The combination stated in claim 1, and a cup-like member spaced within said spiral coil.
- 15 6. The combination stated in claim 1, and a top cover member loosely supported at the outlet of the heater.

NELSON G. GOREAU.
